FUEL RESERVE SUPPLY SYSTEM FOR MOTOR VEHICLES

Filed Dec. 31, 1923

INVENTOR.
Francis Jerdone Jr.
BY *Solon H. Broughton*
ATTORNEY.

UNITED STATES PATENT OFFICE.

FRANCIS JERDONE, JR., OF TOLEDO, OHIO, ASSIGNOR TO THE WILLYS-OVERLAND COMPANY, OF TOLEDO, OHIO, A CORPORATION OF OHIO.

FUEL-RESERVE-SUPPLY SYSTEM FOR MOTOR VEHICLES.

Application filed December 31, 1923. Serial No. 683,683.

This invention relates to fuel reserve supply systems for motor vehicles, and has for one object to provide improved means for controlling the discharge of fuel from the supply tank in order that a predetermined amount of the fuel may be held in reserve, so that in case the driver fails to replenish the supply at the proper time, and the engine stops for lack of fuel, the apparatus can be 10 adjusted to permit the use of the reserve supply, at the same time calling attention to the fact that the tank needs re-filling.

Another object of the invention is to provide a simple and practicable arrangement 15 for controlling the discharge of fuel from the supply tank, constructed so that in addition to affording a reserve supply of fuel, the apparatus can be locked in a position to prevent the discharge of the fuel from 20 the tank at any time desired, thus serving as a means for preventing the theft of the car by cutting off the supply of fuel to the engine.

Another object of the invention is to provide 25 in combination with a fuel supply tank, a fuel control valve having two discharge positions, in one of which a reserve supply of fuel will be maintained in the tank, and in the other of which said supply will be 30 free to discharge therefrom, the valve having still another position at which it is adapted to cut off the discharge entirely, in which position it is adapted to be locked to prevent unauthorized use of the machine.

Other objects will appear from the 35 description to follow, covering certain embodiments of the invention, which, for the purposes of the present application, I have illustrated in the accompanying drawings, 40 in which:

Figure I is a part sectional elevation of a fuel supply tank and valve mechanism, embodying one form of the invention.

Fig. II is an enlarged part sectional elevation 45 of the valve in position to discharge the main supply of fuel, but adapted to prevent the discharge of the reserve supply.

Fig. III is a similar view, with the valve 50 in position to discharge the reserve supply.

Fig. IV is a sectional elevation showing the valve locked in closed position to prevent the discharge of any of the fuel, and hence the unauthorized use of the machine.

Fig. V is a bottom plan view of the valve

in the position shown in Fig. IV, with the lock omitted, the upper and lower dotted line positions of the operating handle indicating respectively, the positions of this member as disclosed in Figs. II and III.

Fig. VI is a sectional plan taken on line VI—VI of Fig. II.

Fig. VII is a sectional plan taken on line VII—VII of Fig. II, and

Fig. VIII is a fragmentary, sectional elevation showing a modified form of valve 65 construction, one permitting the valve to be withdrawn downwardly through the casing upon removal of the handle and packing nut thereabove.

Referring to the drawings, 10 represents a 70 fuel supply tank which may be of any suitable type, located at any desired point upon the automobile, such for instance, as under the cowl (not shown), where it may be supported by the dash 11. The tank is provided with a flange 12, into which is screw-threaded a valve casing 13 having a central bore therein adapted to receive a tubular valve 14 arranged to fit snugly within the bore, but capable of being rotated therein. 80 The tubular member 14 is provided with a stem or operating member 15 projecting thereinto and secured by a rivet 16 extending transversely through the stem and tubular member. The bottom of the tubular member 85 14 rests upon a shoulder 17 on the valve casing, which prevents the downward removal of said member. The stem or operating member 15 is surrounded by a packing nut 18 screwed into the bottom of the casing 90 13 to compress the packing 19 around the stem, whereby to prevent leakage of the fuel past the same.

The stem 15 is provided with a handle 20, 95 removably secured thereon to permit the valve and stem to be inserted within and removed from the casing when desired, said handle being preferably secured by a screw 21 threaded into the end of the stem as shown in Fig. IV. The casing 13 is provided at a point below the tank with an outlet opening 22 in a threaded extension 23, to which is connected a discharge pipe 24, as by means of a coupling 25, the discharge pipe leading to the carburetor of the engine, (not shown), to which the fuel is fed by gravity from the tank 10 in a manner to be explained hereinafter. The valve 14 is pro-

jected upwardly within the tank a distance obtained by determining the height therein of the quantity of fuel desired to constitute the reserve supply.

- 5 As long as the fuel is at a level above the top of the tubular valve 14, it will flow downwardly therein and outwardly through the discharge opening 26, assuming that the latter is in registry with the outlet 22 of 10 the casing, as shown in Fig. II, this being the normal running position for the valve. As soon as the level of the fuel drops below the top of the valve, the flow therethrough is discontinued. It then becomes necessary 15 either to replenish the supply, or to set the valve so that the reserve supply may be used. This is done by turning the valve from the position shown in Fig. II, to that shown in Fig. III, in which position, the outlet 20 opening 27 of the valve will register with the outlet 22, and simultaneously the inlet 28 of the valve will register with the opening 29 in the extended portion 30 of the casing, thus permitting the reserve supply 25 to be discharged to the carburetor. After the reserve supply or any portion of the same has been used, the valve will, at the time of replenishing the tank, be turned back to normal position as indicated in Fig. II.
- 30 In addition to the reserve control feature, the device is so constructed that it can be employed by the driver when parking or housing the car to prevent theft of, or the 35 unauthorized use of the same. To accomplish this result, it is only necessary to turn and lock the valve in the intermediate position shown in Figs. I, IV and V, in which position it will close the outlet 22 and cut off the supply of fuel to the engine, leaving 40 available only the amount in the carburetor, which is insufficient for use in driving the car any considerable distance.

Any suitable locking means may be provided, but I prefer to use a padlock as shown 45 at 31, the bolt of which is extended through the openings 32 and 33 of the handle 20 and arm or extension 34 respectively, the latter being preferably cast integral with the casing 50 13 and also serving as an indicator to indicate that the valve is in closed position when the handle is in registry therewith. If a padlock of proper form and size is selected, it will be impossible for a prospective thief to remove screw 21 and drop 55 handle 20 far enough to enable him to expose the end of stem 15 and thus turn the same. The handle is provided with the lateral extensions 35 on the opposite sides thereof, which are adapted to engage a stop lug 60 36 on the casing when the handle is in either of the dotted line positions shown in Fig. V, corresponding to the running positions of the valve as shown in Figs. II and III.

65 Mounted upon the upper end of the casing in spaced relation to the extension 30,

is a strainer 37, through which the fuel must pass before entering the tube 14, said strainer being secured to the casing by soldering or otherwise, as desired.

The casing and the valve, together with 70 the strainer, form a unitary device, simple in construction and economical to manufacture and one which can be readily detached by unscrewing the same after the coupling 25 has been disconnected from the extension 75 23. The ready application and removal of the device as a single member, effects a considerable saving in time and the accessibility of the parts is of advantage in reducing the cost of repairs. 80

The arrangement shown in Fig. VIII is the same as that already described, except that the longitudinal bore of the casing is extended through to the packing chamber and the tube projected downwardly into the 85 packing nut as shown at 38, thus permitting the tubular valve to be withdrawn downwardly from the casing after the packing nut 18 has been removed. In addition to this change, the valve stem 15 is extended 90 through the handle 39 and the latter secured thereto by a screw 40 positioned at a right angle to the stem, the handle having the laterally extending projections 35, the same 95 as the handle 20, which are adapted to engage the stop lug 36, as shown by dotted lines in Fig. V. By removing the handle 39, the packing nut 18 may be unscrewed and the valve withdrawn by a downward pull on the same. 100

While I have shown and described in considerable detail, certain specific embodiments of my invention, it is to be understood that this showing and description is 105 illustrative only and for the purpose of rendering my invention more clear, and that I do not regard the invention as limited to the details of construction illustrated or described, except insofar as I have included such limitations within the terms of the 110 following claims.

I claim as my invention:

1. In combination with a liquid tank, a rotary valve comprising a casing secured to the bottom of said tank, a stem within 115 said casing having a shoulder thereon co-acting with a portion of said casing to prevent downward withdrawal of said stem, a packing nut engaging said casing and the lower part of said stem for preventing leakage, a downwardly removable handle on said stem below said packing nut, an extension upon said casing, and means for locking the handle to said extension whereby downward movement of said handle on said stem is 120 restricted and said valve component parts are locked together as a unit. 125

2. In combination with a liquid tank, a rotary valve having open and closed positions, comprising a casing secured to the 130

bottom of said tank, a stem within said casing having a shoulder co-acting with a portion of said casing to prevent downward withdrawal of said stem, a packing nut engaging said casing and the lower part of said stem for preventing leakage, an outwardly removable handle on said stem below said packing nut, an extension on said casing, and means for locking said handle to said extension, whereby the component parts of said valve may be locked together as a unit in the closed position of the valve. 10

In testimony whereof, I affix my signature.

FRANCIS JERDONE, JR.
